UNITED STATES PATENT OFFICE.

PROCTOR P. COOLEY, OF PEORIA, ILLINOIS, ASSIGNOR TO CULTER & PROCTOR STOVE COMPANY, OF PEORIA, ILLINOIS, A CORPORATION OF ILLINOIS.

DESIGN FOR A STOVE.

42,931.

Specification for Design.

Patented Aug. 27, 1912.

Application filed June 20, 1912. Serial No. 704,927. Term of patent 7 years.

To all whom it may concern:

Be it known that I, PROCTOR P. COOLEY, a citizen of the United States, and residing at Peoria, in the county of Peoria and State of Illinois, have invented a new, original, and ornamental Design for Stoves, of which the following is a specification, reference being had to the drawing forming a part hereof.

The figure is a perspective view of a stove showing my new design.

I claim:

The ornamental design for a stove, as shown.

PROCTOR P. COOLEY.
